DESIGN FOR A HAIRBRUSH OR SIMILAR
ARTICLEIsadore O. Witte, Los Angeles, Calif., assignor to Le Vant Brush Company, Los Angeles, Calif., a corporation of California

Application December 16, 1946, Serial No. 135,543

Term of patent 3½ years

(Cl. D86—10)

To all whom it may concern:

Be it known that I, Isadore O. Witte, a citizen of the United States, residing in Los Angeles, in the county of Los Angeles and State of California, have invented a new, original, and ornamental Design for a Hairbrush or Similar Article, of which the following is a specification, reference being had to the accompanying drawing, forming part thereof.

Fig. 1 is an elevational view of the back of a hairbrush or similar article, showing my new design.

Fig. 2 is a side elevational view thereof, with the surface ornamentation merely suggested.

Figs. 3 and 4 are enlarged fragmentary sectional views taken on the respective lines 3—3 and 4—4 of Fig. 1.

The dominant features of the design are embodied in the parts shown in full lines.

I claim:

The ornamental design for a hairbrush or similar article, substantially as shown and described.

ISADORE O. WITTE.
